TELEPHONE STAND

Donald Michael Genaro, Haworth, N.J., John Niel McGarvey, Drexel Hill, Pa., and Gordon Elliott Sylvester, Jamaica, N.Y., assignors to Bell Telephone Laboratories, Incorporated, Murray Hill, N.J.

Filed Apr. 13, 1973, Ser. No. 351,101

Term of patent 14 years

Int. Cl. D14—03
U.S. Cl. D26—14 A

FIG. 1

FIG. 2

FIG. 3

FIG. 4

FIG. 5

FIG. 6

FIG. 7

FIG. 8

FIG. 9

FIG. 1 is a perspective view showing the top, front, and one side of one form of our new design for a telephone stand;

FIG. 2 is a top plan view of the form shown in FIG. 1;

FIG. 3 is a front view of the form shown in FIG. 1;

FIG. 4 is a rear view of the form shown in FIG. 1;

FIG. 5 is a side view of the form shown in FIG. 1; the opposite side being essentially a mirror image of the side shown;

FIG. 6 is a perspective view showing the top, front, and one side of another form of our new design for a telephone stand;

FIG. 7 is a top plan view of the form shown in FIG. 6;

FIG. 8 is a front view of the form shown in FIG. 6; and

FIG. 9 is a side view of the form shown in FIG. 6, the opposite side having essentially the same appearance.

We claim:

The ornamental design for a telephone stand, substantially as shown and described.
